AIR COOLING DEVICE

Filed April 10, 1926

UNITED STATES PATENT OFFICE.

ERULAND HARDY, OF ORLAND, CALIFORNIA.

AIR-COOLING DEVICE.

Application filed April 10, 1926. Serial No. 101,214.

This invention relates to a device for cooling the air in rooms.

An object of this invention is the provision of a device of the character mentioned by 5 which air is cooled by the evaporation of a liquid, preferably water.

Another object of the invention is the provision of a device whereby the air in a room may be cooled by evaporation without increasing the humidity of the cooled air.

A further object of the invention is the provision of means for effecting a forced draft to increase the rate of evaporation of the liquid which cools the air by its evaporation.

With the foregoing objects in view, together with such other objects as may subsequently appear, this invention resides in the construction and arrangement of parts hereinafter described and claimed, and illustrated in the accompanying drawings, in which

Figure 1 is a side elevation of my air cooling device, partly broken away.

Figure 2 is a horizontal section taken on 25 the line 2—2 of Figure 1.

Figure 3 is a fragmentary section taken on the line 3—3 of Figure 1, and

Figure 4 is a fragmentary section taken on the line 4—4 of Figure 2.

Referring to the drawings for more detailed description thereof, the device of my invention comprises a container having sides 5 and 6, bottom strips 7 joining the sides 5 and 6, top strips 8 joining the sides 5 and 6, a rear wall 10 and a front wall 11. An apertured vertical plate 12 is disposed near the rear end, and another vertical apertured plate 13 is disposed near the forward end of the device. Spaced horizontal apertured plates 15 and 16 extend from the vertical plate 12 to the forward part of the device. The plates 15 and 16 have spaced apertures running from the plate 12 to the plate 13 and extend thereacross. Between the plates 12 and 13 and above the plate 15 spaced ducts 18, made of metal and covered with a porous material such as a burlap, are disposed, the upper series of ducts resting on the plate 15 and held by the cross strips 8, and the lower series resting on the bottom strip 7 and held by the plate 16 between the apertures of the latter plate. The spaces between both the upper and the lower ducts 18 are designated 19.

Communicating with the upper series of ducts 18 is a duct 20 which leads into a room,

preferably into the upper part of a room, to which, of course, the hot air rises. Communicating with the lower series of ducts 18 is a duct 22 which leads to the same room as that to which the duct 20 leads to, this duct 22 preferably leading to the lower part of a room. A fan 25 is placed in the duct 22 and draws warm air from the room down through the duct 20, through the upper series of ducts 18, back into the compartment between the rear wall 10 and the plate 12 and thence into the lower series of ducts 18, forwardly into the duct 22 and back into the room, as indicated by the arrows 26 in unbroken lines. The fan 25 thus causes a circulation of air 70 through the room and through the device of my invention. The air which is circulated through the room and through my device is cooled by air flowing downwardly and upwardly through the ducts 19 or spaces 19, 75 which are alternately disposed relative to the ducts 18. The air is drawn through the ducts 19 by a fan 27 disposed in the duct 28 formed by the plates 15, 16 and the rear wall 12. The fan 27 causes air to move in the directions 80 indicated by the arrows 29 shown in broken lines. This air is drawn from the atmosphere outside the room to be cooled and passes through the ducts 19 into the chamber or compartment 28 and thence back into the atmosphere. 85

Transverse pipes 31 having apertures therethrough are connected with a water line. The water passes through the apertures in the pipe 31 and wets the porous material 90 which surrounds the ducts 18. The evaporation of the water from the porous material cools the air passing through the ducts 18 and the passage of air through the ducts 19 hastens the evaporation from the porous material and thus more quickly cools the air which is circulated through the room, and through the ducts 18. 95

Although I have shown and described one embodiment of my invention, it is to be understood that the same is susceptible of various changes; and I reserve the right to employ such as may come within the scope of the appended claim.

I claim:

An air cooling device comprising a casing having three compartments disposed above each other, longitudinally extending air conveying pipes disposed in the top and bottom compartments, an air inlet communicating 105 with the top compartment, an air outlet communicating with the bottom compartment, and a fan disposed in the middle compartment.

with the upper set of pipes, an air passage-way placing the upper set of pipes in communication with the lower set, an air outlet 5 communicating with the lower set of pipes, a fan disposed in said outlet, a porous material wrapped around said pipes, means for saturating the material with water, the walls of said central compartment having openings communicating with the upper and lower

compartments, a fan disposed in said central compartment for drawing air through the upper and lower compartments, and into the central compartment, the air in passing through the upper and lower compartments causing a quick evaporation of water from the porous material.

RULAND HARDY.
